UNITED STATES PATENT OFFICE.

ARTHUR F. KNOWLES, OF UPPER MONTCLAIR, NEW JERSEY.

VENTILATING DEVICE.

Application filed October 6, 1926. Serial No. 139,817.

The invention relates to diffusers mounted at the outlet orifices of air conduits serving to supply air to auditoriums, school rooms and the like, and is based on Letters Patent 5 to Hattie A. Knowles, executrix of George E. Knowles, dated Jan. 30, 1917, No. 1,213,884.

The object of the invention is to provide a device analogous to that shown in the above patent, in which the flow of air from the conduit is practically unobstructed in all directions and in which the advantages of adjustment are retained and so disposed as to occupy less vertical height than required by the structure shown in said patent.

The invention consists in certain novel features of construction and arrangement of parts by which the above objects are attained, to be hereinafter described and 20 claimed.

The accompanying drawings form a part of this specification and show the invention as it has been carried out in practice.

Figure 1 is a plan view of the diffuser 25 with certain portions broken away and partly in horizontal section.

Figure 2 is a vertical section taken on the line 2—2 in Figure 1, and partly in elevation.

Similar reference numerals indicate like 30 parts in both the figures.

As shown in the drawings the device consists of two main portions, a base 5 and a bell or cover 6 joined by a single screw 7.

The base 5 is an open cylinder having a 35 horizontal exterior flange 8 at about the midheight, by which the base may be secured to a floor by screws, not shown, or is provided with lugs 9 adapted to be imbedded in a concrete or cement floor and thus hold the base firmly with its cylindrical portion lying closely within the conduit opening 10.

On the interior of the cylindrical wall of the base 5 are equally spaced thickened portions 11, preferably three in number, each of 45 which extends as a vertical lug 12 below the lower edge of the base. These thickened portions extend to the top edge of the base and each is formed with a series of gradually ascending serrations formed as deep notches or partial recesses 13 arranged spirally and each series similar to the others, and from the junction of each thickened portion with the interior of the base 5 extends a radially 50 disposed spider arm 14 all of which unite in

a central hub or boss 15 preferably on a level with the upper edge of the base 5.

All these parts constituting the base are 60 preferably in a single casting but may be separate pieces suitably joined.

The bell or cover 6 is a hollow flattened dome-shaped casting of greater diameter than the base 5 and is provided with three 65 equally spaced downwardly projecting leg members or fins 16 having thin lower ends adapted to engage in the steps or notches 13, and formed with an internal boss 17, drilled and countersunk to receive the shank of a long screw 7 adapted to engage a correspondingly threaded hole drilled and tapped in 70 the boss 15 of the base.

Thus arranged, the bell 6 may be held supported at any height desired above the base within the range of the serrations 13 by loosening the screw 7 and engaging the members 16 in the desired notches 13 and again tightening the screw. In the drawing the bell 6 is shown at its highest elevation with its legs 16 engaged in the uppermost notch 13 of each series; the dotted lines show the bell 80 in an intermediate position, and by engaging the legs in the lowermost notches the periphery of the bell will rest upon the base-flange 8 and the flow from the conduit opening 10 will be stopped. It will be noted that with 85 the exception of the thin legs 16 there are no obstructions to the lateral flow of air between the rim of the bell 6 and upper edge of the base 5, in any of the open positions, thus insuring the desired diffusion of 90 air without perceptible currents in any one direction.

The improved construction permits the bell 6 to be considerably reduced in height, 95 effecting a corresponding reduction in the height of the device when in position. The serrations or notches 13 are preferably rounded so as to be easily cast while the depth is sufficient to insure reliable engagement with the legs 16 when the screw 7 is 100 tightened, and such engagement locks the screw against accidental loosening.

I claim:

1. In a device of the character set forth, a hollow cylindrical base, a plurality of 105 series of ascending serrations disposed spirally on the annular interior of said base concentrically thereto and below the upper edge thereof, a bodily rotatable cover located above said base, downwardly project-

ing legs on said cover, arranged to coact with said serrations to support said cover and permit the rotative adjustment thereof vertically relatively to said base, and a screw 5 connecting said cover to said base and serving to hold said legs in engagement with said serrations.

2. In a device of the character set forth, a hollow cylindrical base, a plurality of series 10 of ascending notched steps formed integrally with said base on its annular interior concentrically thereto and below the upper edge

thereof, a cover located above said base, downwardly projecting spaced legs formed integrally with said cover and adapted to engage with the notches of said steps, a centrally located boss on the interior of said cover, a centrally located boss in said base, and a screw extended through said bosses to hold said cover to said base. 20

In testimony that I claim the invention above set forth, I affix my signature hereto.

ARTHUR F. KNOWLES.
